UNITED STATES PATENT OFFICE.

WILLIAM ANDERSON LAMBERT, OF SOUTH CHARLESTON, WEST VIRGINIA.

PORTABLE ELEVATING SCAFFOLD.

Application filed April 10, 1928. Serial No. 271,638.

This invention relates to a portable elevating scaffold and particularly to a construction embodying a movable carrier supporting a platform adapted to be elevated to 5 different positions.

A scaffold of this character adapted to be quickly and readily moved both vertically and horizontally, for instance in building and painting operations, requires that the 10 control for the several movements of the scaffold be centralized upon the working platform. For this purpose controlling means for elevating the platform are located thereon and connected to the supporting 15 uprights and also controlling means for shifting the carrier horizontally are extended for the height of such uprights so as to be readily accessible from the platform at any desired elevation. It is also desirable to 20 provide means by which the uprights of the elevator may be folded for transportation or storage and rendered extensible to provide the desired height in connection with the work.

25 It is also important to provide a simple form of pawl and ratchet mechanism including a holding member which will apply a brake in one direction of the movement of the pawl. In order to prevent obstruction 30 of the platform by the operating means, the raising levers are disposed practically level with the floor thereof while the operating means for the horizontally movable carrier is adapted to be removed from the operating 35 shaft for the carrier.

The invention has for an object to provide a novel and improved construction of scaffold including a horizontally movable carrier having uprights and a platform connected, for vertical movement upon said 40 uprights, together with means for actuating the carrier operable from the platform at different elevations thereof.

Another object of the invention is to provide an improved construction for elevating the platform of the scaffold including winding drums mounted upon the platform and having connecting cables extending to the upper portion of the supporting uprights together with pawl and ratchet means for operating the winding drums and means for retaining them in fixed position.

A further object of the invention is to present a new construction of portable ele-

vating scaffold in which means shifting the 55 carrier horizontally are mounted thereon and provided with a vertically extending shaft adapted to be rotated from the platform of the scaffold in its various elevated positions relative to the carrier.

A still further object of the invention is to provide an improved operating lever for engaging the shaft extended from the carrier for imparting a horizontal movement thereto, such lever being adapted for removable application as desired.

Other and further objects and advantages of the invention will be hereinafter set forth and the novel features thereof defined by the appended claims.

In the drawings:

Figure 1 is an elevation showing the invention applied;

Figure 2 is a top plan;

Figure 3 is an enlarged vertical section;

Figure 4 is a section on line 4—4 of Figure 3;

Figure 5 is a similar view of line 5—5 of Figure 3;

Figure 6 is a detail section on line 6—6 of Figure 3;

Figure 7 is an elevation of the operating lever for the carrier;

Figure 8 is a section on line 8—8 of Figure 7;

Figure 9 is a detail perspective showing the extensible sections of the carrier operating shaft; and

Figure 10 is a similar view of the extensible sections of the supporting uprights.

Like reference characters designate corresponding parts throughout the several figures of the drawings.

The scaffold may be constructed of any desired material, size, or configuration dependent upon the character of work to which it is to be applied and the load to be carried thereby. When used for purposes such as painting or surface finishing, the parts may be of comparatively light construction so as 100 to be quickly moved in position, both vertically and horizontally, as the work rapidly progresses. When used for building purposes and the platform designed to carry a load of material, a heavier construction 105 would be desirable.

In the present application of the invention the numeral 11 designates a base or

carrier which is designed to be shifted horizontally for instance upon the supporting wheels 12 and when desired to secure a proper level, tracks 13 may be used for this purpose, altho if the carrier is operated on a level base such tracks would not be necessary. Various means may be used for shifting the carrier, for instance, a cable 14 may be secured at its opposite ends 15 upon proper supports and wound around a drum 16 carried by the operating shaft 17 having a pivot 18 upon the carrier. This shaft is extended vertically for any desired height and for that purpose an extensible section 19 may be used which seats upon the pivoted end 17 of the shaft as shown at 20.

The shaft 17 is adapted to extend through an aperture 21 in the platform 22 of the scaffold and this shaft is also braced by a bracket 23 carried by this platform. The shaft is preferably formed with a rectangular face adapted to receive an operating lever 24 which is applied at the upper face of the bracket 23 and adapted to be removed from the shaft when not in use. This lever 24 comprises a bill or hook 25 formed by opposite plates 26 which are slotted at 26' and carry the pivot 27 of the engaging jaw 28 having its opposite end 29 extended for operation and held in a position away from the lever 24 by the spring 30. The face of the engaging jaw 28 may be angular to fit the face of the shaft 17 and is held in engagement therewith as shown in Figure 8. Inward pressure upon the jaw will release it from the shaft 17 and permit vertical adjustment thereon to the height most convenient for the operator upon the platform. If it be desired to entirely remove the lever 24, for instance, to avoid obstruction when working on the platform, the jaw 28 may be slid rearwardly with its pivot 27 transversing the slot 26' which leaves the hook open for lateral removal from the angular shaft.

The base or carrier 11 is provided with supporting uprights 31 at its opposite ends, these being preferably arranged at the corners of the platform 22. These uprights may be of angular construction as shown in Figure 4 and cooperate with rollers 32 upon the inner and outer faces of the platform. The platform is also provided with brackets 33 secured thereto and carrying rollers cooperating with a vertical track 35 mounted upon the cross members connected to the uprights. This provides against movement of the platform either longitudinally or transversely upon the uprights. In order to vary the height of the uprights for buildings of different elevations they are adapted to be formed of extensible sections as indicated at 36 in Figures 1 and 10, the upper section being similar in construction to the lower and connected thereto by any desired means such as the plates 37, one of which

overlaps the uprights carrying the other plate.

When it is desired to transport or store the scaffold, the uprights may be conveniently collapsed or folded downward and for this purpose the extensible sections 36 are removed and the members 31 which rest upon the carrier 11 are connected thereto by a pivot, such as the hinge 38 which is secured to the carrier and to a cross plate 39 connecting the uprights at each end of the carrier. This plate is provided with an aperture 40 for the passage of the cable 14 by which the carrier is horizontally shifted. To resist any tendency of the uprights to swing on their pivotal connection they may be suitably held by the braces 41 detachably connected to the uprights and sides of the carrier as shown in Figure 1.

For the purpose of elevating the platform 22 a winding shaft 42 is pivotally mounted beneath the same in any suitable manner, for instance, pivoted in the end plates 43. This shaft has secured at its opposite ends winding drums 44 from which cables 45 extend to a connection 46 at the top of the uprights, as shown in Figures 1 and 10.

The shaft 42 has secured thereto a winding ratchet 43 which cooperates with a pawl 44 pivotally mounted at 45 upon the lever 46 which is forked at its inner end 47 to embrace the ratchet 43 and freely swing upon the shaft 42. The pawl is normally held in engagement with the ratchet by a spring 48 interposed between the handle of the pawl and the lever 46, as shown in Figure 6. An oscillating movement of this lever effects a winding of the shaft and drums causing a consequent elevation of the platform upon the uprights.

In order to prevent an accidental release of this pawl and the consequent downward movement of the platform a holding lever 49 is provided and formed with a pawl 50 engaging a ratchet 51 also secured to the shaft 42 and this holding pawl is held under tension in contact with the ratchet by means of a rod 52 extending from the lever 49 and tensioned downwardly by a spring 53 engaging the head 54 on the rod, as shown in Figure 5. When this holding pawl is released to permit downward movement of the platform, it is essential to apply a brake and the lever 49 carries brake straps 55 which cooperate with drums 56 at each side of the holding ratchet 51, the opposite end of this strap being secured at 57 to the platform while the inner end of the lever 49 is also connected to the platform by a pivoted joint 58.

The platform 22 is preferably provided with an extended shelf portion 60 pivotally connected to the inner edge of the platform as at 61 and retained against downward movement by a brace 62 engaging a relative-

ly fixed part. By this means the platform can be extended immediately adjacent the building or work so that the operator can most conveniently reach the same.

5 The operation of the invention will be generally apparent from the foregoing description from which it will be seen that means are provided for horizontally adjusting the carrier from the platform of 10 the scaffold and that this scaffold may also be adjusted vertically and held in its adjusted positions by means upon such platform. These means involve a lever for the operation of the winding drums carried by 15 the platform and an independent holding lever by which the platform may be released for downward movement and a braking action effected during such movement. In the release of the platform the pawl of 20 the winding lever is retracted and the holding lever raised against the tension of its retaining spring. The invention also presents a very efficient form of a detachable 25 operating lever for the carrier travel which is adapted for vertical adjustment upon the shaft from the carrier extending through the platform and also is removable from this shaft laterally thereof under certain conditions of use.

30 The platform is guided upon the uprights and held against movement by the corner rollers thereon and also the guide rollers which resist any longitudinal displacement. The platform when raised to its position of 35 use may be extended toward the building by the pivoted portion which is swung into a horizontal plane parallel with the platform and permits the operator to closely approach the work.

40 While this specific construction has been herein shown and described the invention is not confined thereto as changes and alterations may be made without departing from the spirit thereof as recited in the following 45 claims.

What I claim is:—

1. In a portable elevating scaffold, a carrier, means connected with the carrier for moving the same horizontally, uprights upon 50 the carrier, a vertically movable platform between the uprights, elevating means connecting the uprights and platform, means on the platform to operate the elevating means, a winding device mounted upon the 55 platform, and a holding and braking device upon said platform for controlling the downward movement thereof.

2. In a portable elevating scaffold, a carrier, means for moving the same horizontally, 60 uprights upon the carrier, a vertically movable platform, elevating means connecting the uprights and platform, means on the platform to operate the elevating means, a vertical shaft extended from the carrier moving means through said platform, and an

operating device for said shaft accessible from said platform.

3. In a portable elevating scaffold, a wheeled carrier, uprights extended from said carrier, a vertically movable platform connected to said uprights, a winding drum mounted on the carrier, a fixed cable co-operating with said drum, an operating shaft for said drum extended vertically through the platform and parallel to said uprights, 75 and a detachable operating lever for said shaft disposed adjacent the platform.

4. As a sub-combination in a portable elevating scaffold, an operating shaft, a lever comprising a hook to embrace said shaft, and 80 a jaw mounted upon the hook to interlock with said shaft.

5. As a sub-combination in a portable elevating scaffold, an operating shaft, a lever comprising a hook to embrace said shaft, a 85 jaw mounted upon the hook to interlock with said shaft, and means to effect a longitudinal movement of the jaw relative to the hook to permit a lateral withdrawal of the hook from said shaft.

6. In a portable elevating scaffold, a base, uprights mounted thereon, a platform between said uprights mounted for vertical movement upon said uprights, a winding shaft upon said platform provided with a 95 drum, a cable extending from said drum to the upper end of an upright, means upon said scaffold for rotating said shaft, and means upon said scaffold for retaining said shaft in position and applying a brake 100 thereto when the shaft is released.

7. The combination defined by claim 6 in which the shaft winding means comprises a pawl and ratchet member, and the shaft holding means includes a holding pawl co-operating with a ratchet on the shaft and a 105 brake engaging means upon said shaft.

8. In a portable elevating scaffold, a base, uprights supported thereon, a platform vertically movable upon said uprights, a winding shaft carried by said platform and provided with drums at its opposite ends, cables extending from said drums to said uprights, a ratchet wheel secured to said shaft, a winding lever pivoted upon said shaft, and a 110 pawl mounted upon said lever to engage said ratchet wheel.

9. In a portable elevating scaffold, a base, uprights supported thereon, a platform vertically movable upon said uprights, a winding shaft carried by said platform and provided with drums at its opposite ends, cables extending from said drums to said uprights, a ratchet wheel secured to said shaft, a winding lever pivoted upon said shaft, a 115 pawl mounted upon said lever to engage said ratchet wheel, a holding ratchet secured to said shaft and provided with a brake drum, a lever pivoted to the platform and provided with a pawl engaging said holding 120

125

130

ratchet, and a brake strap secured at one end and connected to the holding lever at its opposite end to engage the drum upon withdrawal of the holding pawl from its ratchet.

5. 10. In a portable elevating scaffold, a base, uprights pivotally mounted thereon, to fold downward when the scaffold is collapsed, a platform, elevating means extending from said platform to the upper end of said up-

rights, means upon the platform for actuating the elevating means, friction rollers at the front and rear of the platform engaging said uprights, vertical tracks at the opposite ends of the platform, and rollers upon the platform engaging said tracks. 10
15

In testimony whereof I affix my signature.

WILLIAM ANDERSON LAMBERT.
